The dominant features of my new design are shown in solid line in the drawing. The piano keys fragmentarily shown by means of broken lines are continuous across the keyboard as indicated by the dash-dot line.

I claim:

The ornamental design for a keyboard controlled musical instrument, substantially as shown and described.
